(57) **CLAIM**

The ornamental design for a vehicle exterior rearview mirror head, as shown and described.

(**) Term: **14 Years**

DESCRIPTION

(21) Appl. No.: **29/484,546**

FIG. 1 is a front perspective view of the vehicle exterior rearview mirror head design;

(22) Filed: **Mar. 11, 2014**

FIG. 2 a rear perspective view of the vehicle exterior rearview mirror head design;

(51) LOC (10) Cl. **12-16**

FIG. 3 is a front elevation view of the vehicle exterior rearview mirror head design;

(52) U.S. Cl. **D12/187**

FIG. 4 is a rear elevation view of the vehicle exterior rearview mirror head design;

(58) **Field of Classification Search**

FIG. 5 is a left side elevation view of the vehicle exterior rearview mirror head design;

USPC D12/187, 188-189; D6/300, 309;
359/838, 844, 868, 871, 604, 881, 514,
359/866; 248/479-483, 475.1

FIG. 6 is a right side elevation view of the vehicle exterior rearview mirror head design;

See application file for complete search history.

FIG. 7 is a top plan view of the vehicle exterior rearview mirror head design; and,

(56) **References Cited**

FIG. 8 is a bottom plan view of the vehicle exterior rearview mirror head design.
